G. J. CARROLL

AUTOMATIC GRAVE CLOSING OR COVERING DEVICE

Filed June 20, 1924

Inventor
GEORGE J. CARROLL

By A. D. Jackson
Attorney

UNITED STATES PATENT OFFICE.

GEORGE J. CARROLL, OF GAINESVILLE, TEXAS.

AUTOMATIC GRAVE CLOSING OR COVERING DEVICE.

Application filed June 20, 1924. Serial No. 721,220.

My invention relates to a covering device for graves and more particularly to a temporary covering for graves; and the object is to provide a covering which will be automatically actuated by the casket lowering mechanism so that the grave will be closed so that the casket will be hidden from view. With such provision, the bereaved parties and others will not have to stand and watch the covering of the casket with dirt and the sadness of the occasion will be lessened or shortened and the services at the grave can be closed so that all parties may leave. Other objects and advantages will be fully explained in the following description and the invention will be more particularly pointed out in the claims.

Reference is had to the accompanying drawings which form a part of this application.

Fig. 1 is a perspective view of the frame work without the lining and covering, the frame work being suspended in the cavity. Fig. 2 is a perspective view of the covering after it has closed the grave. Fig. 3 is a vertical cross-section of the covering, as shown in Fig. 2. Fig. 4 is an enlarged detail view, showing the manner of connecting the longitudinal frame members to the curved end members. Fig. 5 is a plan view of the devices shown in Fig. 4. Fig. 6 is a broken view of the telescoping longitudinal members. Fig. 7 is a perspective view of one end of a curved end member, showing the provision for spring engaging members on the ends of the longitudinal frame members.

Similar characters of reference are used to indicate the same parts throughout the several views.

The drawings show the usual lowering mechanism consisting of the rolling side members 1 and 2 which are journaled in the bearing members 3, one of which contains the gearing for lowering the casket by means of the straps 4, and the end members 5.

The principal parts of the closing device are two quarter segmental members, indicated generally in Figs. 2 by A and B. The lowering devices are provided with two boards 6 and 7 and spindles 8 which are mounted in the sides of the boards 6 and 7. Two pairs of frame members are provided

at each end of the mechanism. Each frame member consists of a radial bar 9 and a curved member or arc 10 and these members are pivotally mounted on the spindles 8 and swing on these spindles, Fig. 1 showing the frame members in inoperative position and Fig. 3 showing these end frame members in closed position. Longitudinal telescopic bars 11 and 12 are connected to the arched members 10 of the end frame members. The members 10 are provided with notches 13 and the telescopic members 11 and 12 are provided with spring grabs 14. The spring grabs 14 are provided with beveled lugs 15. The grabs are shoved against the edges of the members 10. The beveled portions of the lugs 15 will cause the spring grabs to open to receive the frame members 10 and when the lugs 15 reach the cut-outs 13, the lugs will drop into the cut-outs 13. This operation will secure the longitudinal frame members to the end arch members 10. The ends of the arch members 10 are provided with abutments 16 which serve as braces when the device is in closed position. The two longitudinal members 17 are supported by two spring detents 18 which are riveted to the end members 10. With this provision, should the casket tend to come against the longitudinal members 17, the casket would bear against the spring detents 18 and this would push the longitudinal members 17 out of the way of the casket. The telescopic member 11 is provided with a series of holes 19 and the member 12 carries a spring 20 which carries a lug for dropping into the holes 19 for holding the telescopic members 11 and 12 at any required adjustment. A lining 21 of silk or any suitable material is attached to the longitudinal bars 11 and 12 and to the end members 10. A coarser covering 22 is attached to the outside of the longitudinal members 11 and 12 and to the end frame members 10. The covering 22 may be provided with a ruffle or fringe 23 for partly closing the ends of the segmental members A and B. The segmental members A and B are actuated by chains 24 which are attached to the rollers 1 and 2 of the lowering device by suitable clamps and the other ends of the chains are attached to the end members 9 and 10 at the juncture of the members 9 and 10. When the lowering device is lowering the casket, the segmental

covering members A and B will be automatically swung up to the positions shown in Fig. 2 and in Fig. 3.

Provision is made for closing the ends of the segmental covering. End closing frame members, similar to members 9 and 10, are attached to the radial bars 9. These end closing members include radial bars 25 which are attached to the bars 9 and arched spring members 26 are riveted to the members 25. Any suitable cloth 27 is attached to the arch spring members 26 to hang down as shown in Fig. 2. The end closing members move with the arch or segmental members A and B.

Various changes in the construction, arrangement, dimensions, and proportions of the several parts may be made without departing from my invention.

20 What I claim, is:—

1. A grave closing mechanism comprising a pair of segmental frames, each frame consisting of a pair of end radial members and curved members attached thereto and telescopic longitudinal detachably connected to said curved members, end frame members connected to said radial members, coverings attached to said end frame members, coverings for said segmental frames inclosing the curved portions thereof, pivotal bearings for said segmental frames to permit the swinging of said frames down into the grave cavity and the swinging of said segmental frames out of the cavity to cover a casket, and means for automatically actuating said frames as a casket is lowered into the grave.

2. The combination of a casket lowering mechanism and a grave closing mechanism comprising a pair of segmental members provided with telescopic longitudinal frame members and having their ends closed and the curved surfaces thereof covered, pivotal bearings for said segmental members for permitting said members to swing down into the grave cavity and to swing out of the grave cavity for inclosing a casket, said

arched members having notches near their ends and said longitudinal members having spring grabs engaging said arched members in said notches, and means operatively connecting said segmental members to said casket lowering mechanism for automatically actuating said segmental frame members to cover the casket as it is lowered into the grave.

3. A grave closing mechanism comprising a pair of segmental frames, each frame consisting of radial end members and arch members connected thereto and longitudinal members provided with spring grabs for engaging said arch members, coverings for said frames, pivotal bearings for said segmental frames to permit the swinging of said frames down into the grave cavity and the swinging of said frames out of the cavity to cover a casket, and means for automatically actuating said frames as a casket is lowered into the grave.

4. The combination of a casket lowering mechanism and a grave closing mechanism comprising a pair of segmental members provided with means for adjusting said members longitudinally, each segmental member consisting of arched members provided with notches near their ends and longitudinal members provided with spring grabs having beveled lugs adapted to engage said arched members in said notches, coverings for said members, pivotal bearings for said segmental members for permitting said members to swing down into the grave and to swing out of the grave cavity in position to cover a casket, and means operatively connecting said segmental members to said casket lowering mechanism for automatically actuating said segmental members to cover the casket as it is lowered into the grave.

In testimony whereof, I set my hand, this 15th day of May, 1924.

GEORGE J. CARROLL.
